SALVAGE BUOY

Eugene J. Romano, Seattle, Wash.

Application October 12, 1931, Serial No. 568,375

6 Claims. (Cl. 114—53)

5 My invention relates to buoys intended for salvaging sunken vessels, and is of that type of which a considerable number are attached by lifting lines to the vessel while the buoys are submerged, air being subsequently forced into the buoys to displace the water therein through a normally open port in the bottom, to render the buoys buoyant.

10 Such buoys in use are subjected to swaying motions and to tilting, and this is particularly true as they lie at or approach the surface, and during such movement buoys open at the bottom are likely to lose air, and in consequence to become less buoyant, so that it is difficult to cause the 15 buoys to bring a sunken ship all the way to the surface, or to retain it there for any length of time. It is an object of my invention to provide such a buoy normally open at its bottom, but so formed that air can be lost from its interior only with difficulty, even under pronounced 20 swaying movement.

25 To aid in moving such buoys from place to place, it is desirable that they be enabled to float upon the surface, and it is an object of my invention to provide gravity-controlled means associated with such buoys, whereby when in a horizontal floating position (the water having been previously expelled) the normally open port will be kept closed to keep out the wash of sea water, 30 and preferably one which also is gravity-controlled to open when the buoy is brought to its vertical or lifting position.

35 It is desirable in the use of such buoys that the attendant on the salvage vessel at the surface know how much water remains in each buoy, and how nearly each buoy is approaching its maximum buoyance. It is therefore an object of my invention to provide a means, automatically operable, which will convey this information to the attendant 40 on the salvage vessel, and it is particularly an object to provide float-controlled electrical means for this purpose.

45 Such buoys being subjected to the crushing effect of high hydrostatic pressures, it is an object to devise internal bracing which will prevent collapse of the buoy, and which in addition will transmit from the lifting lines to the several parts of the buoy the lifting stresses, so as to distribute the same, and in addition to design such 50 internal bracing means in a form which will permit cranes upon the salvage vessel to assist the lifting effect of the buoys by a line from above attached to the buoy, and which will transmit such lifting effort to the lifting lines attached to the 55 vessel itself, without strain on the buoy itself.

These and other objects will be best ascertained from a study of the accompanying drawings and of this specification and the claims.

In the accompanying drawings I have shown my invention in a form which is at present preferred by me, and have so described it in the present specification, whereof the claims particularly point out that which I believe to be my invention.

Figure 1 is an elevation of a buoy floating in 60 towing position.

Figure 2 is an elevation, with parts broken away, of a buoy tilted from lifting position.

Figure 3 is an axial sectional view of a buoy in lifting position.

Figure 4 is a diagram of the electrical indicator 70 circuits.

While the buoy 1 is a vessel which may take substantially any form, it should have greater length than breadth, so that it will tend to rise in a given upright position, or when floating free 75 on the surface it will assume a horizontal position. It may conveniently be made cylindrical, as shown herein, having the top 10 and the bottom 11. Its bottom is provided with an open port 12 admitting to the interior, and a neck 2 is secured to the bottom 11, providing an extension below the bottom, whereby the actual entrance to the interior is at the lower end 22 of the neck. The purpose of this is seen in Figure 2, wherein the buoy is shown in a tilted position, for even in such 80 position the air will not escape from the interior of the buoy through the opening 22, but will remain trapped within the neck.

To displace the water with which the buoy is 85 filled to sink it, an air hose 3 may be attached by a suitable fitting 13, preferably at the top of the tank. The air hose, as it will be understood, extends to the surface, where it is connected to any suitable source of air under pressure (not shown). If the bottom 11 is coned downwardly, as I prefer, 90 all the water will be expelled, though the buoy be tilted. To control the buoy in its descent, and under some circumstances to assist in lifting it, there may be attached to its top 10 means such as the ring 14 for the attachment of a lifting line 100 4, likewise extending to the salvage vessel at the surface.

At the bottom of the buoy are means for securing lifting lines 5, and such means may take the form of rings 15, two of which are shown arranged 105 in crossed form and secured at 16 to the neck 2.

In order to brace the buoy internally, and in addition, to transmit lifting effort from the eye 14 to the rings 15, to transmit the straight lifting effort centered at the rings 15 to all parts of the 110

buoy, and to distribute such efforts, it is desirable to provide internal bracing means, which, in the present instance, are shown in the form of diagonal braces 6 and 60, connecting the bottom and top respectively with the sides of the buoy intermediate the ends, and cross braces 61 connecting opposite points of securement of the braces 6 and 60. The braces 6 and 60 may in fact constitute one integral member, and the upper braces 60 10 are preferably connected through the head 10 to the eye 14, the same rivet 62 being employed to secure both members to the head, and at the bottom the braces 6 are connected directly to the rings 15 through the neck 2 by employing the 15 same rivets 16 as support the rings. Stresses are thus transmitted from the eye 14 to the rings 15 without passing through the buoy itself, and the lifting effort of the buoy is thus distributed by the internal bracing to all parts of the buoy rather than centered at the neck alone. This enables parts to be made lighter, yet without materially decreasing the buoyance of the buoy, or reducing its strength.

Within the neck 2,—that is, within the port or 25 passage which admits to the interior of the buoy through the bottom—I provide a valve 7, preferably of the butterfly type, pivoted at 70 upon a ring 71, which forms a seat therefor. Externally of the neck there is an arm 73, connected to the 30 valve, to which is secured a counterweight 72 by means of which the valve 7 is maintained normally in a vertical plane. Now when the buoy is upright, the valve 7 being likewise upright, will not close the passage, as will be observed in Figure 3, but if the buoy, being empty of water, is placed upon the surface, it will assume a horizontal position, in which case the valve 7, remaining upright, will close the neck 2 to passage of water therethrough. This position may be observed in 40 Figure 1, and in this position the buoy can be towed by a line 44 attached to the eye 14, from one location to another. Naturally, means may be provided to additionally seal the opening at such times. Unless means are provided to prevent it, 45 the valve will assume an open position when the buoy is drawn upright, and when in this position will freely admit passage of water or air through the neck 2.

I prefer that the buoy be provided with means 50 for indicating while submerged to the attendant upon the salvage vessel the depth of water within the buoy itself,—that is to say, the location of the water level within the interior of the buoy. Such means may take various forms. As an example, it may be in the form of a float 8 guided 55 for movement longitudinally of the float, as for instance upon the rod 80. Such a float is shown provided with a contact member 81, and there are positioned adjacent the path of movement of this contact member, complementary contacts 82 and 83 connected in the respective lines 84 and 85, extending through the conduit 87, attached at 88 to the buoy, and these lines in turn are connected to the individual indicators 86, which are located 60 upon the salvage vessel.

As the water level within the buoy drops (the water being expelled by air entering through the 65 hose 13 and passing out through the open neck 2) the float 8 drops, and as it drops, the contact 81 in turn closes the circuits including the spaced contacts 82 and 83, in order from the top downward, and these circuits being closed cause the

corresponding indicator lights 86 to be illuminated, and in this manner the attendant can follow the progress of the water level downwardly, and from experience, or by calibrations, can know the amount of lifting effect which each buoy, and 80 which all of the several buoys, exert at any given period. To protect the contacts, they may be coated with a suitable resistant coating, which will not prevent the passage of the electricity, but will prevent the contacts from corroding.

Except as required for the support of the valve 7 or for the securement of the lifting lines and bracing, the neck 2 may be flexible. It may be rigid at its upper end, adjacent the buoy, and flexible therebelow. If made flexible wholly or 90 in part, it may be of such length that, once water is expelled, the interior of the buoy will be effectively water-sealed against accidental entrance of water, or sloshing thereinto.

The manner of use of my buoy will be clear, 95 and the apparatus and system for connecting and controlling the same forms the subject matter of a companion application, filed herewith, and is described in detail therein.

What I claim as my invention is:

1. A salvage buoy comprising a vessel of greater longitudinal extent than breadth, having a normally open port at one end, and gravity-controlled means to close said port when the vessel is disposed horizontally, as in floating upon the surface. 105

2. A salvage buoy of greater longitudinal extent than breadth, having a normally open port at one end, and gravity-controlled means to close said port when the vessel is disposed horizontally, as in floating upon the surface, and to open said 110 port when the vessel is upright, as in lifting.

3. A salvage buoy of substantially cylindrical form having a restricted neck coaxial with and projecting below its bottom, said neck being normally open to afford access to the interior of the 115 buoy, a valve of the butterfly type disposed in said neck, and a weighted arm operatively connected therewith to close said neck when the buoy is horizontal, and to open the same when the buoy is upright.

4. A salvage buoy of substantially cylindrical form and of greater longitudinal extent than breadth, having an open port in its bottom, means for attaching lifting lines to the bottom of the buoy, means axially aligned with the first means 125 for attaching towing and lifting lines to its top, and internal bracing means connecting the two attaching means.

5. A salvage buoy of substantially cylindrical form and of greater longitudinal extent than breadth, having an open port in its bottom, means for attaching lifting lines to its bottom, means axially aligned with the first means for attaching towing lines to its top, and internal bracing means connecting the two attaching means, and reinforcing the intermediate portion of the buoy against collapse. 135

6. In combination, a cylindrical salvage buoy, a coaxial neck projecting below one end to afford normally free access to the interior of the buoy, means to supply air to the interior to displace the water therein, internal bracing connecting the top and sides of the buoy to the neck, and rings for the connection of lifting lines connected externally of the neck, and to the internal 140 bracing.

EUGENE J. ROMANO.
